FIREARM

Crawford C. Loomis, Ilion, N. Y., assignor to
 Remington Arms Company, Inc., a corporation
 of Delaware

Application May 18, 1933, Serial No. 671,626

4 Claims. (Cl. 42—41)

This invention relates to firearms, and contemplates certain improvements in sear control and particularly in safety mechanisms.

The invention has been illustrated as applied to a firearm of the type disclosed in the patent to Loomis, No. 1,900,184, March 7, 1933; although it is to be understood that its utility is not limited to firearms of this particular type. Said patent describes a firearm of the "upward tilting breech" type in which an assembly of one or more barrels is pivoted on a horizontal pivot near the forward end of a breech mechanism frame, and upon the release of certain locking devices normally swings upwardly relative to said frame to open the breech. Guns of this type may include one, two or three barrels, and in the two barrel type the barrels may be arranged either side-by-side or one above the other. A shiftable safety device is usually provided, serving when in one position to block the firing movement of the sear or trigger or both. Such a safety device is ordinarily under the control of a finger piece projecting upwardly through the "tang" or top plate of the frame. There may be three positions for such a device, one "safe" position and two firing positions. The arrangement may be such that the unlocking or opening movement of the breech will automatically move the safety device from one of its firing positions to "safe" position, while, if the safety device has been manually placed in the second firing position it is not affected by the unlocking or opening of the breech. The safety controlling finger piece is usually arranged to move longitudinally of the firearm, and the position in which it is not affected by the unlocking or opening of the breech is its rearmost position.

It has been shown that safety mechanisms of this type are subject to the defect that the recoil of the gun incident to firing may shift them from their rearmost position to their intermediate "safe" position. Such movement occurs irregularly and without the knowledge of the shooter and becomes a source of confusion and annoyance, particularly in double guns in which a quick firing of the second barrel may be desirable.

It is an object of the present invention to provide a safety device which is positively latched in the position to which it is adjusted by a latching device which must be moved in a direction different from the direction of movement of the safety device in order to permit shifting of the safety device.

55 A further object of the invention is to provide

a positively latched safety device requiring movement of the latching means as a preliminary incident to any movement of the safety device itself.

A further object of the invention is to so arrange the safety latch control that the operator, in preparing to shift the safety in the usual way, will shift and disable the latch substantially involuntarily.

A further object of the invention is to provide means associated with the unlocking or opening of the breech for first disabling the safety device latch and subsequently moving the safety device to render the gun safe.

The invention further contemplates certain improvements in the control of sear mechanisms, as will hereinafter more fully appear.

In the drawing:

Fig. 1 is a fragmentary, longitudinal elevation, partly in section, of a fire control mechanism 20 including one embodiment of the invention.

Fig. 2 is a fragmentary top plan view of the firearm shown in Fig. 1.

Fig. 3 is a fragmentary transverse section substantially on the line 3—3 of Fig. 1.

Fig. 4 is a fragmentary sectional side elevation showing the parts in the position they assume when the breech has been unlocked with the safety mechanism in its foremost firing position.

Fig. 5 is a perspective view of the safety mechanism latch and a fragment of the safety slide.

In the firearm illustrated in the drawing the fire control mechanism is supported in a frame comprising a lower member or trigger plate 10 and a top member or tang 11 connected by and preferably integral with a post 12.

One train of mechanism only will be described, it being understood that in double guns such parts as firing hammers, sears, etc., may be duplicated.

The firing hammer 13, sear 14, and trigger 15, are all supported on the trigger plate or parts directly connected therewith. The sear 14 is preferably pivoted at 16 between sear housing plates 17 suitably secured to the trigger plate. A single trigger mechanism of a suitable type such for example as that disclosed in the prior co-pending application of Loomis, Serial No. 616,234, filed June 9, 1932, may be provided. Such a mechanism comprises a connector 18 pivoted to the trigger and designed to oscillate from one to the other of the two sears 14 under the control of actuators 19 cooperating with the ham-

mers 13 and other devices more fully described in said Loomis application.

The breech mechanism is locked by a locking bolt in the form of a sliding breech cover 20, 5 which cover is retracted to unlock the breech by manipulation of a top lever 21 pivoted to the tang 11 at 22 and connected with the breech cover 20 at 23. A safety operating plunger 24 is connected to the top lever at 25, and the top lever 10 is urged to breech closing position by means of a spring 26 preferably coiled about the safety operating plunger 24 and abutting a lug or post 27 depending from the tang.

One feature of the present invention includes 15 the control of the sear 14 by a spring so applied thereto as to exert its force in the direction of movement of the hammer engaging portion of the sear. Such a spring is shown at 28 surrounding a spring pilot 29, which pilot is engaged with 20 the sear at a point substantially opposite the hammer engaging nose 30. The opposite end of the spring pilot 29 is received in an aperture 31 in the lug 27, which lug also furnishes an abutment for the spring 28. Hitherto, sear springs 25 have been associated with the trigger plate and, while tending to rock the sear about its pivot, have not acted upon the sear in the direction of movement of the hammer engaging portion thereof. By the mechanism above described the sear 30 is pressed directly toward the hammer, with improved functioning, as well as simplification of the mechanism.

The safety mechanism comprises a safety bar 32 having in its lower end an elongated slot 33 35 which embraces the sear pivot 16. A lug 34 on the safety bar 32 cooperates with a laterally extending stud 35 on the tail of the sear. Said lug may occupy a position in front of the stud 35, as illustrated in Fig. 1, or a position in rear of said 40 stud, in either of which positions the sear is free to execute its hammer releasing movement. In the intermediate position, illustrated in Fig. 4, the lug is directly below the stud 35 and movement of the sear is blocked. The position of the 45 safety bar 32 is determined by the position of a safety slide 36 which works in a longitudinal slot 37 in the tang 11. Said slide 36 is provided with a depending projection or foot 38 having a forward extension 39 which is pivotally connected 50 at 40 to a fork 41-42 integral with the bar 32. Above the tang 11 is a safety operating finger piece 43 rigid or integral with the safety slide 36. Said piece is of sufficient length and width to cover the slot 37 in any of its positions. Its 55 forward portion may comprise an aperture 44 through which the legend "Safe" on the tang insert 45 is visible when the safety mechanism is in safe position. The finger engaging portion thereof is preferably concave to provide for easy movement in either direction without shifting the position of the finger. It will be seen that the finger piece 43 and safety slide 36 may occupy any one of three positions corresponding to the three positions of the safety bar 32 heretofore described.

65 It will be seen that all parts of the safety mechanism as thus far described move in a direction longitudinal to the frame of the gun. If the safety mechanism is in its rearmost firing position the recoil of the gun upon firing may 70 throw the gun frame rearwardly with respect to the safety mechanism, said mechanism being at this time as at all times free to move relative to the frame, with the result that such firing 75 leaves the sear 14 locked, and the finger piece 43

must be manually shifted before a second firing can take place.

Single trigger guns are particularly susceptible to this type of malfunctioning, inasmuch as the sear which is actuated to release one of the hammers is freed from the trigger immediately upon the fall of its hammer and returns to its hammer engaging position, leaving the safety bar and connected parts entirely free for movement. To obviate this difficulty, and for reasons of general safety, the present invention contemplates a safety latching mechanism, one form of which has been illustrated in the drawing and is described as follows:

The safety slide 36 is provided with a vertical 15 shouldered aperture and within this aperture is placed a latch plunger 46. Said plunger is urged upwardly by a spring 47 interposed between the shoulder 48 of the aperture and a shoulder 49 on the plunger. The upper end of the plunger is 20 formed as or has secured thereto an operating head or finger piece 50, which projects into the concavity of the safety finger piece 43 in position to be substantially automatically depressed when the gun operator engages the finger piece 43 for 25 the purpose of shifting it. Below the tang 11 the latch plunger 46 is secured to or enlarged to form one element of a locking device comprising upwardly facing elements cooperating with counterpart elements on the underside of tang 11. The 30 locking device may take various forms. As illustrated in the drawing it comprises a cross head 51 secured to plunger 46 comprising one or more beveled lugs 52 which cooperate with notches 53 formed on the underside of the tang or on a plate 35 secured to the tang. To secure the accurate guiding of plunger 46 which is desirable for easy manipulation said plunger may be extended downwardly and its lower end received in a suitable aperture 54 (Fig. 3) in the extension 39 of 40 the safety slide foot 38. It will be seen that by reason of the engagement of the lugs 52 with notches 53 the safety mechanism is positively latched in one of its three positions and cannot be displaced from this position without lowering 45 the lugs out of the notches. The necessary depression of the lugs may be effected by manually depressing the head or finger piece 50, or by a second means which will now be described.

It is desirable that provision be made for the 50 movement of the safety mechanism from its foremost firing position to "safe" position upon the unlocking of the breech. This necessitates first moving the latch device downward to disengage the lugs 52 from notches 53 and subsequently 55 shifting the safety mechanism rearwardly. The means for securing this result are as follows: Secured to the latch assembly 46-51 is a block 55 comprising a forwardly and downwardly inclined cam surface 56 and adjacent to and above said cam surface a vertically disposed face or shoulder 57. Upon the rear end of the safety operating plunger 24 (actuated by the top lever 21) is an inclined face 58 and above said face a square shoulder 59. The positioning of these parts 65 is such that, upon the breech opening movement of the top lever 21 and the consequent rearward thrust of plunger 24, the inclined face 58 of the plunger engages the cam surface 56 of the latch assembly and draws the latch downward to disengage lugs 52 from notches 53. To prevent distortion or undue strain upon the latch during this camming movement, a rearward face 60 on block 55 is made to engage and slide upon a forward face 61 of the safety slide foot 38. In the con- 70 75 75

tinued rearward thrust of plunger 24, the latch having been disengaged, shoulder 59 of the plunger engagess the shoulder 57 and thrusts the safety mechanism rearwardly to its intermediate or 5 "safe" position. When the gun is closed and top lever 21 restored to its normal position, plunger 24 moves forward, permitting the latch assembly to rise, bringing lug 52 into the intermediate notch 53.

10 It should be noted that the gun is automatically rendered safe by opening the breech only when the safety mechanism is in its forward firing position. When the safety mechanism has been placed in its rearmost firing position by depressing 15 the latch finger piece 50 and drawing the finger piece 43 to the rear, it is not affected by opening the breech. Moreover, since displacement of the safety mechanism from any position to which it has been set requires distinct and separate movement in each of two directions it cannot be effected by the jar due to recoil or to any accident.

20 The embodiment of the invention herein described is illustrative only, the invention being susceptible to various modifications, all falling 25 within the scope of the appended claims.

What is claimed is:

1. In a firearm, in combination, a frame, a breech locking mechanism, a safety mechanism comprising a member slidably mounted in said 30 frame, a latch movably mounted in and normally positively holding said member in any of a plurality of positions, a manipulative device for disabling said latch, a bar adapted to be displaced by said breech locking mechanism, and cooperat- 35 ing cam surfaces on said bar and said latch where-

by upon the unlocking movement of said breech locking mechanism said latch is first displaced and said slideable member subsequently shifted.

2. In a firearm, in combination, a frame comprising a tang and a trigger plate, a retractable breech locking mechanism comprising a spring, an abutment for said spring on said tang, a sear supported from said trigger plate, and a sear spring interposed between said trigger plate and said abutment. 10

3. In a firearm, in combination, a frame comprising a tang and a trigger plate, a spring abutment on said tang, a sear supported from said trigger plate, and a sear spring interposed between said trigger plate and said abutment. 15

4. In a firearm, in combination, a frame having a plurality of locking notches, a retractable breech locking device, a cam associated with said device, a sear, a safety bar adjustable into and out of locking relation with said sear, a safety slide comprising a concave finger piece in said frame, a foot on said safety slide having a pivoted connection with said safety bar, a latch for said slide comprising a plunger slidably mounted therein, a head on said plunger extending into the concave of said finger piece; and a foot on said plunger guided by the foot on said slide, said plunger foot comprising a cam surface cooperating with said breech locking device cam and a locking projection cooperating with the locking notches on the frame to positively hold the safety slide in any one of a plurality of positions until said latch is depressed to remove said projection from any of said notches. 20 25 30
